No. 844,948.

PATENTED FEB. 19. 1907.

E. P. LYNCH.
STATIONERY HOLDER.
APPLICATION FILED JAN. 19, 1906.

UNITED STATES PATENT OFFICE.

EDWARD P. LYNCH, OF SALT LAKE CITY, UTAH.

STATIONERY-HOLDER.

No. 844,948.

Specification of Letters Patent.

Patented Feb. 19, 1907.

Application filed January 19, 1906. Serial No. 296,866.

To all whom it may concern:

Be it known that I, EDWARD P. LYNCH, a citizen of the United States, residing at Salt Lake City, in the county of Salt Lake and 5 State of Utah, have invented certain new and useful Improvements in Stationery-Holders; and I do hereby declare the following to be a full, clear, and exact description of the invention, such as will enable others 10 skilled in the art to which it appertains to make and use the same.

This invention relates to improvements in stationery-holders.

The object of the invention is, primarily, 15 the construction of a paper or a letter-paper support and holder in such a manner that certain requisite conditions are met—namely, the holding of one or more sheets of paper in comparatively fixed position, the protecting 20 of the paper from being soiled by contact with the hand in writing, and the providing of a continuous and uniform support for the hand while the top sheet is being written upon. Secondarily, the addition to this 25 paper-holder of other elements comprising, primarily, a hinged cover containing holders for the envelopes, stamps, and other essentials used in letters and letter-writing, and a calendar by which dates covering several 30 future years are convenient to the user.

With these and other objects in view the invention consists of certain other novel combinations, constructions, and arrangements of parts, which will be fully described, illustrated in the accompanying drawings, and more particularly pointed out in the claims 35 hereto appended.

In the drawings, Figure 1 is a top plan view of the holder in an open position. 40 Fig. 2 is a vertical longitudinal central sectional view of the holder in a closed or folded position, the same being shown substantially twice the size as in Fig. 1.

The lower half of Fig. 1 represents the 45 paper support and holder or paper-pocket. While the paper support or back is preferably made of material having some stiffness, it can be so gaged and made of such length that by doubling a portion of the piece upon 50 itself to an extent sufficient to form the pad and cover 4 and by securing the turned-up end to the back 1 by means of an elastic or other fabric the paper-holding pocket is formed. Should the stiffness of the piece 1 55 be such that it could not readily be bent, suitable material could be used in connec-

tion with piece 1 and bent up to form the front 4 of the pocket and also the cover 2 if such an addition is wished. In forming a cover in this way the material would be 60 doubled upon itself, the bend forming a hinge, as at 3. By these means an almost complete paper-holder could be made from one piece of material. The face of the pocket, however, can be made of a separate 65 piece, and this can be of blotting-paper or other suitable material to which, if desired, a blotter can be firmly or removably secured. The latter method is shown in Figs. 1 and 2.

The fastening 5 secures 4 to the back 1, and thus forms the pocket 6. A blotter 7 is held in place on the pad by having its corners placed in the corner-pieces 5. While the blotter 7, secured to the piece 4, is a convenience and in a way improves the pad as a resting-place for the hand, it may not be used, for in the various constructions described a detached blotter held when not in use in any one of the pockets will meet the 80 average need. The paper-pocket formed in any of the ways referred to is preferably made in sizes to suit the dimensions of standard writing-papers and is arranged to hold few or many sheets. The lower end of the 85 sheets 8 is placed in the pocket. The size of the pocket is such that the paper is held in position without a top fastening, the face of the pocket 4, being large enough to protect a large portion of the paper-surface from 90 being soiled by contact with the hand, and forms a pad for the hand to rest on when writing, and during the act of writing the sheet is drawn from the pocket by successive movements. The hand has a uniform sup- 95 port and with reference to the body retains its relative position with but little change while writing from the top to the bottom of the sheet. The weight of the hand when but few sheets remain in the pocket tends by its 100 pressure on the pad to hold them steady.

While the paper-pocket arranged substantially as described embodies the essential features and could be used effectively without additional conveniences, I improve it by 105 adding a cover 2 and other accessories. The cover 2 can be made as already described or be formed of a separate piece and hinged to back 1, as at 3. Preferably I make the cover 2 of a length so that one end 9 can be 110 doubled upon itself and forms, with cover 2, a pocket 10, similar to the paper-pocket, this

5 pocket 10 to be used for holding envelops. The pocket 10 is formed in such way that when the cover 2 is closed upon back 1 the envelop-pocket covers the upper portion of the sheets 8, which is held in the paper-pocket and does not conflict with that receptacle. The edge of pocket 10 is preferably strengthened by the reinforcing material 11, which also forms the fastening to secure it to the piece 2. Reinforcing-pieces 12 may also be used, all being secured by suitable adhesive material. The cover 2 when closed, if of sufficient length, will protect the upper part of sheet or sheets 8. I prefer the cover 15 to be of such length as will cover the entire length of back 1, especially if the removable blotter is used, in which case the cover 2 can be held closed by inserting its outer corners in the pocket 6. In addition, I place, preferably, above the envelop-pocket 10 a flexible piece 14, secured to 2 by adhesive material, and preferably the reinforcing-pieces 15, and for convenience form upon one side 20 of 14 by means of the longitudinal slits 16 a pen or pencil holding device. The upper portion 17 of piece 14 forms a clamp-like holder and is designed to hold stamps or memorandums by forcing them wedge-like between the cover 2 and the piece 14.

30 As this paper-holder is in a special way intended to supply the conveniences necessary for correspondence I plan a calendar covering a series of the coming years so designed that the paper-holders made in succeeding years shall, with the calendar for the year in which they are made, have those for several years to come, and preferably place it upon the face 10 of the envelop-pocket, and for the same reason I add the postal 35 regulations and plan to use unused spaces for advertising matter. The calendar device in a special way meets the needs of the average user, dealer, and manufacturer. To the manufacturer of holders and dealers in them there need be no question of the holder-stock getting out of date, and the user has the assurance of years of a device that all 40 know the value of.

45 The novel holder which I have herein described can be made of the cheapest material and at a trifling cost or elaborately of the finest material.

50 What I claim is—

55 1. In a device of the character described, the combination of lower and upper hinged backs, a pad carried by said lower back, said pad provided with a pocket, the upper back adapted to be partially positioned within said pocket for securing said backs in a folded 60 position, said pad and lower back producing a pocket therebetween.

65 2. In a device of the character described, the combination of an upper and a lower back, a flexible strip connecting one of the ends of said backs, a pad secured to the

lower back, said pad and back producing a pocket formed therebetween, said pad provided with strips at each of its corners, said strips and pad producing pockets, the upper back adapted to be positioned within some of 70 said pockets for securing said backs in a folded position.

3. In a device of the character described, the combination of a cover composed of connected backs, a blotter-pad carried by one of 75 said backs, a pad secured to said back, said pad with the back forming a pocket, and fastening means formed upon said blotter-pad for securing said backs in a folded position.

4. In a device of the character described, 80 the combination of a cover composed of movably-connected backs, a blotter-pad positioned between said backs and secured to one of the same, said pad provided with pockets at each end, a blotter supported 85 upon said pad and positioned within its pockets, and said pad and lower back provided with a pocket formed therebetween.

5. A holder, comprising connected upper and lower backs, a blotter-pad secured to 90 said lower back, said pad and lower back provided with a pocket formed therebetween, said pad provided with pockets formed at its corners, the outer corners of the upper back adapted to be positioned within the 95 pockets of said pad for securing said backs in a folded position, and article-supporting means carried by said upper back.

6. In a device of the character described, 100 the combination of connected backs, a blotter-pad carried by one of said backs, a pad secured to one of said backs, said pad with said back forming a pocket, fastening means carried by said blotter-pad for securing one 105 of said backs in a folded position with the other back, and article-supporting means formed between said body and lower back upon the inner face of said upper back.

7. A stationary holder, comprising movably-connected upper and lower backs, a pad 110 secured to one of said backs, said pad with said back forming a pocket, a blotter-pad secured at its ends and one of its longitudinal edges to said lower back, said pad provided with pockets at each of its corners, some of 115 said pockets adapted to receive the upper back for securing the same in a closed position with the lower back, said upper back folded at one end for producing a transverse strip, a pocket formed between said strip and 120 upper back, a slitted strip secured at its sides to the inner face of said upper back, the slitted portion of said strip constituting a rack, and a pocket formed between said slitted strip and the upper back.

8. In a device of the character described, 125 the combination of upper and lower hinged backs, a pad carried by said lower back, said pad being provided with a pocket.

9. A device of the character described, 130

comprising a support provided with a pocket, and a cover hinged to said support and provided with a receiving-pocket, the said pockets in the said cover and support being arranged so as not to conflict when the cover is closed.

10. A device of the character described, comprising a back, a cover hinged to said back, having an article-holding sheet provided with clamp-like ends, secured thereto, and a pad secured to said back, said pad with said back forming a pocket.

11. In a device of the character described, the combination of a cover composed of connected backs, a pad secured to one of said backs, and forming a pocket thereon, and means for securing said backs together when in their folded position.

In testimony whereof I affix my signature in presence of two witnesses.

EDWARD P. LYNCH.
